UNITED STATES PATENT OFFICE.

ISAIAH C. VAN FOSSEN, OF PUEBLO, COLORADO, ASSIGNOR OF ONE-HALF TO HARRY A. DEUEL, OF PUEBLO, COLORADO.

SPIKE-MAKING MACHINE.

1,400,392.

Specification of Letters Patent. Patented Dec. 13, 1921.

Application filed June 12, 1919. Serial No. 303,616.

To all whom it may concern:

Be it known that I, ISAIAH C. VAN FOSSEN, a citizen of the United States, residing at Pueblo, in the county of Pueblo and State 5 of Colorado, have invented certain new and useful Improvements in Spike-Making Machines, of which the following is a specification.

This invention relates to machines for 10 making spikes and its object is to provide a machine which is adapted to make spikes of all sizes and lengths and all of the various types, such as standard rail spikes, boat spikes, mine rail spikes and special track 15 spikes with either standard or reversed points. My machine may also be used to make special shaped bolts.

In most cases existing machines for the manufacture of spikes are only adapted to 20 produce one particular type while those which can be used for different sizes or types require considerable time to make the necessary changes in the machine. In my machine the changes in the tools required to 25 adapt the machine to make different types of spikes may be effected in a few moments, so that the machine is universal in its adaptation to spike making. Moreover, I have greatly simplified the mechanism of spike 30 machines and have so correlated the operating parts that the output is very greatly increased over prior machines.

For the purpose of explaining my invention, I shall refer in the following description 35 to the accompanying drawings, in which Figure 1 is a perspective view of a spike machine embodying my invention; Fig. 2 is a top plan view and Fig. 3 is a side elevation of the same; Fig. 4 is a perspective view 40 of the cutting tool holder; Fig. 5 is a top plan view of the machine without the feeding device and with certain parts omitted; Fig. 6 is a vertical sectional view on the line 6—6 of Fig. 5; Fig. 7 is a perspective view of the 45 cross-head connected to the cutting tool holder; Fig. 8 is a longitudinal vertical section on the line 8—8 of Fig. 2; Fig. 9 is a perspective view of the header; Fig. 10 is an enlarged detail sectional view of the 50 header bearing taken on the line 10—10 of Fig. 8; Fig. 11 is a transverse vertical section on the line 11—11 of Fig. 2; Fig. 12 is a perspective view of the spike clamping 55 tool; Fig. 13 is a transverse vertical section on the line 13—13 of Fig. 2; Fig. 14 is an

end view of the spike machine viewed from the left side of Fig. 5; Fig. 15 is a perspective view of the kicker rod; Fig. 16 is a perspective view of the cam shaft actuating the header and cutting tool; Fig. 17 is a perspective view of the cam shaft actuating the spike gripping lever, spike pointing tool and kicker rod; Fig. 18 is a perspective view of the tool holder for the pointing tool; Fig. 19 is a perspective of the bottom plate 60 for the latter; Fig. 20 is an end elevation of the automatic feeding device; Fig. 21 is a vertical section on the line 21—21 of Fig. 2; Fig. 22 is a transverse section on the line 22—22 of Fig. 20; Fig. 23 is a cross section 70 on the line 23—23 of Fig. 2; Fig. 24 is an enlarged fragmentary view illustrating the operation of the pointing tool; Fig. 25 is a perspective view of the cutter and its holder or box; Fig. 26 is a fragmentary top plan 75 view showing an auxiliary heading device coöperating with the heading tool; and Fig. 27 is a vertical section of the same on the line 27—27 of Fig. 26.

The machine may be either direct connected to the driving motor or be belt driven. I have shown the main shaft 2, provided with fast and loose belt pulleys 3, 4 and fly wheel 5. The machine is provided, as usual with a cutting tool to cut the required length 80 from the blank, a gripping lever, a header lever, and a pointing lever, which operate in proper sequence.

The header lever, 10, illustrated in Figs. 8 and 9, is provided with a forwardly projecting portion 10^a having a slot 12 to receive the various header tools 11. The outer end is provided upon the under side with a hardened plate 14, which engages the actuating cam 15 on the shaft 2. The shank 95 portion 16 is formed with an offset portion upon each end to provide a double set of bearing seats 17, 18, within which are secured boxes 19, carrying bushings 20, to receive the pivot pins 21, mounted in boxes 100 23 adjustably secured in a depending portion 1^a of the main frame 1. The angular movement and leverage of the lever 10 may be readily changed by shifting the pivot pins from one pair of bearing seats to the 105 other pair.

The cutting tool lever 26 is mounted to swing on the vertical pivot 27 and is provided with a socket 28 to receive the cutting tool 29. The cutting tool lever is connected 110

by the link 32 with the sliding cross-head 34 which is reciprocated by the eccentric strap member 35 surrounding the eccentric 36 on shaft 2. The cover plate which is bolted to the top of the cross-head, as shown in Figs. 1 and 2 is omitted in Figs. 5, 6 and 7. Coöperating with the cutting tool 29 is a stationary cutter 40, which is clamped in a slotted tool holder or box 41. The cutter blade 40 and box 41 as well as the frame abutment 1^b, are beveled at the proper angle to coöperate with the tool 29 in severing a spike length 37^a from the blank.

The blank 37 fed into the machine rests upon a ledge 43^a on the stationary gripping blocks 43, which are removably clamped between the frame abutments 1^b 1^c by the bolts 45. Coöperating with the gripping blocks 43 is a gripping tool 47 carried by the gripping lever 48, the tool 47 having a recessed or notched forward edge which engages the top and inner side of the spike blank 37^a when the lever is advanced into gripping position.

The gripping lever, shown in Fig. 12 is provided with an elongated shank 49, recessed at the ends to receive bushings which constitute bearings for the pivot pins 50, upon which the lever is oscillated by the cam 52 on the shaft 53. The outer end of the lever may be provided on the under side with a hardened wear plate 55. The shank 49 may be recessed as shown at 49^a to permit the reciprocation of the header lever 10, the side of the lever being provided with a notch 48^a into which the front end of the header tool box 10^a projects when in its forward position. The gripping tool 47 is removably held in the tool recess 48^b by screws threaded in the tapped holes 57.

Simultaneously with the advance of the lever 10 to head the spike 37^a, a pointing tool holder or box 60, carrying a pointing tool 61, is advanced by the cam 63, on the shaft 53 and forces the end of the spike from the position shown in Fig. 24, into the final position shown in Fig. 5, thereby forming the pointed end between the tool 61 and the beveled end of the box 41. The recess in the outer end of the heading tool 11, is of the proper configuration to give the desired shape to the head of the spike as is well understood.

When the spike has been formed in the manner described, the header, gripping tool and cutter are retracted as the cams are withdrawn and the kicker bar 65 is moved forward by the engagement of the pin 66 on the disk 67 with the lug 68 on the kicker bar, thereby causing the kicker pins 70, to push the finished spike off of the ledge 43^a. The pins 70 pass through apertures in the plates 43.

The automatic feeding mechanism for intermittently feeding the blank bar into the

spike machine is carried in standards 80. The lower feed roll 81 is positively driven while the upper roll 82 merely rotates in frictional engagement with the bar as it is fed forward. The lower feed roll is connected through gearing 83, 84 with a shaft 85 which carries upon its outer end a toothed ratchet disk 87, the latter being inclosed in a housing 89 formed of mating members bolted together and carrying a pawl 90 which engages the teeth of the ratchet disk 87. The housing 89 is loosely journaled on the shaft 85 and is intermittently oscillated by means of a connecting rod 92, the opposite end of which is journaled on a pin carried by the slotted disk 94 on the end of the main drive shaft 2, the pin being adjustable in the slot 93, to vary the throw of the pin and consequently the length of stroke made by the connecting rod. The length of the oscillating movement of the housing 89 may be varied by adjusting the pin 95 along the slotted guides 96 carried by the housing. In this manner the length of the spike blank fed into the spike machine at each oscillation may be varied to suit the desired conditions, so that the machine can be quickly adjusted to make spikes of different lengths.

The blank bar which is fed into the guides 97 is grasped by the feed rolls 81 and 82 and at each forward oscillation of the housing 89 and ratchet disk 87 the blank is fed forward through the guide 98 and along the flange 43^a of the plates 43 until the end of the bar is adjacent the header. By positively driving only the lower feed roll and allowing the upper roll to be rotated merely by the frictional engagement with the blank bar, the adjustment of the feeding roll may be arranged to over-feed the blank as the rolls will slip when the part fed into the machine is stopped. The guide 98 may conveniently be formed of a pair of channel-irons as shown in Fig. 23 and the inner end is yieldingly held in position by the spring 99 so that it may be permitted to yield laterally to accommodate the bending movement of the bar as it is being severed by the cutting tool 29.

I have previously pointed out that the various tools in the machine may be quickly changed when it is desired to vary the size or shape of the spikes. In Figs. 26 and 27 I have illustrated a modification of the heading mechanism which is especially adapted for standard spikes in which the head is usually offset to one side of the body of the spike. I provide an auxiliary lever 100 shaped substantially as shown and which is pivoted on a bolt 102 so that it may swing in a horizontal plane on the axis of the spike. The bolt may have a squared shank so that it will be held from turning within the rectangular slot 104 formed in the base of the main frame, the bolt having 130

an elongated head 103 which covers the aperture at all times. The bolt may be adjusted to different positions along the slot to vary the throw and angularity of movement of 5 the portion which engages the head portion of the spike blank. The lever is provided with a suitable socket to receive the heading tools 105 and is also provided with a hardened wear plate 106 which is engaged 10 by the header as it moves forwardly to head the spike. In this case the header strikes the lever 100 instead of striking the end of the spike blank and swings it on the pivot bolt 102 which may be provided with a 15 bearing bushing 107. The side motion of the heading tool 105, due to the swinging of the lever 100 upon the pivot bolt assists in forcing the metal of the head laterally to produce the offset head of the standard 20 spike.

The operation of the machine will be understood from the foregoing detailed description of the structural parts. The end of the blank bar is inserted between the 25 guides 97 until it is grasped by the feed rolls 81, 82, and is fed forwardly by the intermittent movement of the feed rolls which are actuated by the oscillating movement of the shaft 85 which is intermittently driven from 30 the power shaft 2 through the connecting rod 92, operating through the ratchet disk 87 and pawl 90 in the manner previously described. The pivot bolt 95 is adjusted along the guide bars 96 attached to the housing 89 until the oscillating movement causes 35 the spike length of blank to be fed into the machine at each reciprocation of the connecting rod 92. The end of the blank rod 37^a now rests on the ledge 43^a of the blocks 43. 40 The gripping lever 48 swings forwardly under the action of the cam 52 until the gripping tool 47 bears against the spike blank, clamping the latter firmly against the blocks 43, see Fig. 11. The cams 15 and eccentric 45 36 on shaft 2, next cause the header 10 to swing forwardly simultaneously with the movement of the cutter lever 26, thereby severing the spike blank from the bar and heading the spike. Following in sequence 50 the pointing lever 60 slides forwardly under the action of the cam 63, forcing the pointing tool 61 against the end of the blank in the manner illustrated in Figs. 24 and 5. Immediately thereafter the cams release the 55 header and gripping levers and permit them to swing backwardly on their pivots. The pointing lever is retracted by a spring 60^a which holds it against the cam 63. As this takes place the stud 66 on the disk 67 engages 60 the lug 68 on the kicking lever 65 causing the latter to move forwardly until the kicker rods 70, sliding through holes in the blocks 43, push the spike off of the ledge 43^a.

My machine is designed especially to permit the tools to be readily changed and the

throw or amount of periodic movement of the several operating parts to be easily and quickly altered to suit different conditions so that the machine may be readily altered to make different sizes and varying types of 70 spikes.

The heading tool in the header lever, the pointing tool in the pointer lever or box, and the cutting tool in the cutter lever, may be readily changed, while the throw or angular 75 movement of the header lever may be altered by shifting the pivots 21 from the sockets 17 to 18 or vice versa. The stationary gripping blocks 43 and the cutter blade 40 and its holder 41 may be removed or replaced by 80 loosening the screws 45. Likewise the amount of rotation of the feed rolls 81, 82 at each oscillation of the connecting rod 92 may be varied by adjusting the bolt 95 in the guides 96. My machine is therefore a 85 universal machine since adapted for making spikes of different sizes and lengths and different types such as standard rail, mine rail, track and boat spikes, special bolts, etc.

I claim:—

1. In a spike making machine, a gripping lever, a heading lever, a pointing lever, a kicking bar lever, and separate cam devices for actuating said respective levers.

2. In a spike making machine as set forth 95 in claim 1, the heading lever being provided with a plurality of pivoting means adapted to be connected to the machine, whereby the center of rotation and amount of angular movement of the lever may be altered as desired.

3. In a spike making machine, a gripping lever, a heading lever, a pointing lever, a kicking bar lever, the heading lever moving in a plane at right angles to the movement of the gripping lever and the pointing lever, and interconnected drive shafts perpendicularly arranged and provided with cams actuating the heading lever and the gripping and pointing levers respectively, whereby each 105 lever is actuated by a cam operating in direct alinement therewith.

4. A spike machine as set forth in claim 1, wherein the cutting off lever is actuated by an eccentric on the drive shaft and is connected therewith by a reciprocating cross-head and a connecting rod or link.

5. A spike machine having a cam-actuated main heading lever, and an auxiliary lever pivotally mounted to move between the 120 spike blank and the main heading lever and to be driven forward by the latter against the blank to form the head on the spike.

6. In a spike machine as set forth in claim 1, a feed device operating to automatically 125 advance the blank bar into the machine, cutting mechanism to cut off a spike length, and a guide member extending between the feed device and the cutting mechanism, the guide member being yieldably mounted to permit 130

lateral movement as the spike length is being severed from the bar.

7. A spike machine having a cutting tool box or holder provided with a removable cutting blade and stationary blocks provided with ledges to support the blank bar as it is fed into the machine, said holder and said blocks being detachably secured in the machine frame, a cutting off lever provided 10 with a tool adapted to coöperate with said

cutting blade, and a gripping lever provided with a gripping tool adapted to coöperate with the ledge portions of said blocks to clamp the blank during the spike-forming operations.

15

In testimony whereof I affix my signature.

ISAIAH C. VAN FOSSEN.
